LUMINAIRE

William B. Elmer, Boston, Mass.

Application March 5, 1957, Serial No. 45,104

Term of patent 14 years

(Cl. D48—31)

Fig. 1 is a side elevation of a luminaire, showing my new design.

Fig. 2 is a top plan view of Fig. 1.

Fig. 3 is an end elevation looking toward the right end of Fig. 1.

Fig. 4 is a bottom plan view.

Fig. 5 is a section looking to the left and taken on the line 5—5 of Fig. 1.

Fig. 6 is a somewhat enlarged cross-sectional view of the end shade elements taken on the lines 6—6 of Fig. 1 and Fig. 3.

The dominant features of my design reside in the portions shown in full lines.

I claim:

The ornamental design for a luminaire, as shown and described.
